[57] CLAIM

The ornamental design for an electronic book, as shown and described.

DESCRIPTION

FIG. 1 is front perspective view of an electronic book showing my new design in a mostly opened position; FIG. 2 is a front elevational view thereof in a fully opened position;

FIG. 3 is a front elevational view thereof in a partially opened position;

FIG. 4 is a right side elevational view thereof in a fully closed position;

FIG. 5 is a left side elevational view thereof;

FIG. 6 is a top plan view thereof in an opened position;

FIG. 7 is a bottom plan view in an opened position;

FIG. 8 is a rear elevational view thereof in a fully opened position;

FIG. 9 is a front elevational view thereof, in a fully closed position;

FIG. 10 is a top plan view thereof in a mostly closed position;

FIG. 11 is a bottom plan view thereof; and,

FIG. 12 is a rear elevational view thereof.

It is understood that the stippled shading representing contrasting color extends continuously across the surface where it is shown.
